METHOD OF MAKING FABRIC COVERED BAG FRAMES

William C. Hiering, Newark, N. J., assignor to
The J. E. Mergott Company, Newark, N. J., a
corporation of Delaware

Application June 7, 1935, Serial No. 25,362
Renewed August 10, 1937

4 Claims. (Cl. 113—116)

This invention relates to frames for ladies' hand bags and the like, and more particularly to a method for conveniently and effectively covering frames with fabric, leather or similar material.

5 Heretofore, hand bag frames, for example of the channel type, have been first formed of metal blanks and bent generally into a U-shape, after which the fabric or leather was applied thereto.

10 In applying the material to the frame, it was the practice to cut the material into strips and coat one side thereof with a liquid adhesive, and then attach the strips to the completely formed frame. This method obviously was tedious and inconvenient, requiring considerable time, and objectionable to such an extent that many bag manufacturers would send the frames out to other establishments especially for the purpose of having the frames covered with fabric, leather or other material.

15 It is, therefore, an object of this invention to provide a method for effectively and conveniently covering metal hand bag frames with fabric and other materials during the formation of the hand bag frame itself.

20 A further object is the provision of a fabric having adhesive tape attached to one side thereof to enable the ready application of the fabric to a hand bag frame without necessitating the application of liquid adhesive to the strip as here-
30 tofore has been the case.

25 A further object is the provision of a method whereby a metal blank can be readily covered with a fabric or other material, and the blank subsequently bent into a channelled U-shaped hand-
35 bag frame which is in condition for immediate use in the manufacture of a hand bag.

These and other advantageous objects, which will later appear, are accomplished by the simple and practical construction and arrangement
40 of parts hereinafter described and exhibited in the accompanying drawing, forming part hereof, and in which:

Fig. 1 is a plan view of a metal blank which is for forming a channelled U-shaped handbag frame.

45 Fig. 2 is a perspective view showing the blank formed into a channel.

Fig. 3 is a perspective view showing the channel in Fig. 2 subsequently bent into a U-shape, and
50 Fig. 4 is a perspective view of a portion of fabric having adhesive tape or the like attached to one side thereof.

In accordance with my invention, a blank 4, as shown in Fig. 1, has one side thereof completely covered with fabric 5, the fabric extending

over and covering a portion of the other side of the blank. The fabric 5, as shown in Fig. 4, has one side thereof provided with adhesive tape 6 or a similar cementitious material which is provided substantially integral with the fabric, 5. The adhesive tape 6 obviously facilitates the application of the fabric to the blank 4, as it is only necessary to press the adhesive tape on to the blank in the proper position and thereby obviating the necessity of using glue or other liquid adhesives as heretofore has been necessary in applying fabric to metal hand bag frames.

After the blank 4 has been covered as above described, it is placed in a machine and formed into a channel 7 as shown in Fig. 2, after which 15 the channel 7 is bent into a U-shaped frame 8 as disclosed in Fig. 3.

Due to the ability of the adhesive tape to stretch slightly, without material deformation, when the channel 7 is bent into the U-shape as shown in Fig. 3, there will be no puckering of the fabric at the corners 9, and the fabric will lie smoothly on all parts of the frame and have a pleasing appearance.

In some instances it may be desirable to first 25 form the metal blank into the channel 7 before applying the fabric. In such cases, it is apparent that by using a fabric 5 having a coating 6 of adhesive tape or the like attached thereto, the applying of the fabric to the channel 7 is greatly 30 facilitated.

From the above description, it will be seen that by employing a fabric having a strip of adhesive tape attached thereto, it is possible to conveniently and effectively cover hand bag frames of any shape. Obviously the methods herein 35 described greatly facilitates the attaching of fabrics and similar material to frames, and obviates the necessity of using liquid adhesives, which are generally objectionable and messy, in the covering 40 of articles with fabric.

The foregoing disclosure is to be regarded as descriptive and illustrative only and not as restrictive or limitative of the invention, of which obviously an embodiment may be constructed including many modifications without departing from the spirit and scope of the invention as denoted in the appended claims.

Having thus described my invention, what I claim as new and desire to secure by Letters Patents, is:

1. The method of providing a U-shaped hand bag frame with a fabric covering, comprising covering a metal blank with the fabric, attaching said fabric to the blank by means of an adhesive then

bending the covered blank into a channelled member, and then bending said member into a U-shaped frame member.

2. The method of making a hand bag frame 5 with a covering of fabric or similar material, comprising covering a metal blank with a fabric having adhesive tape attached to one side thereof, then bending the blank into a channelled member, and then bending said member into a U- 10 shaped frame.
3. The method of making a hand bag frame with a covering of fabric or similar material, comprising covering a blank with a fabric pro-

vided with an adhesive substance on one side thereof, then bending the blank into a channelled member, and then bending the member into a U-shaped frame.

4. The method of making a hand bag frame 5 with a covering of fabric or similar material, comprising forming a metal blank into a channelled member, covering the channelled member with a fabric having an adhesive substance on one side thereof, and then bending the channelled 10 member into a U-shaped frame.

WILLIAM C. HIERING.
